UNITED STATES PATENT OFFICE.

ESTEN PELOUBET, OF ALEXANDER, ARKANSAS.

INSULATOR.

SPECIFICATION forming part of Letters Patent No. 554,723, dated February 18, 1896.

Application filed November 1, 1895. Serial No. 567,618. (No model.)

To all whom it may concern:

Be it known that I, ESTEN PELOUBET, a citizen of the United States, residing at Alexander, in the county of Pulaski and State of 5 Arkansas, have invented certain new and useful Improvements in Insulators; and I do hereby declare the following to be a full, clear, and exact description of the invention, such as will enable others skilled in the art to which 10 it appertains to make and use the same.

This invention relates to certain new and useful improvements in insulators for telegraph and telephone lines and other uses, and has for its objects, among others, to provide 15 a simple, cheap, and durable insulator, not liable to be broken, and in which the parts shall be protected from snow, ice, and the like.

Other objects and advantages of the invention will hereinafter appear and the novel 20 features thereof will be particularly pointed out in the appended claims.

The invention is clearly illustrated in the accompanying drawings, which, with the letters of reference marked thereon, form a part 25 of this specification, and in which—

Figure 1 is a perspective view of my improved insulator with the cap lifted. Fig. 2 is a vertical section through the same. Fig. 3 is a horizontal section taken in line with 30 the insulators.

Like letters of reference indicate like parts throughout the several views.

Referring now to the details of the drawings by letter, A designates the base, preferably of cast-iron, having two substantially 35 parallel openings a therethrough, said openings each having a slot a' communicating therewith and through which the line-wire may be inserted. Into this opening, which 40 is provided with the communicating slot, are inserted the semicircular glass cylinders B, while in the other opening are inserted the glass spools or cylinders C. In practice the line-wire D is inserted into this opening 45 through the slot above mentioned and then the semicircular glass plates are placed in position to retain the line-wire. The cylinders in the other opening are placed in position and the tie-wire E passed therethrough 50 and made fast about the line-wire in the

usual manner. The base is provided with a screw-threaded opening A' to receive the pins in use on all lines, and by which means the insulator will be supported upon the post.

F is a cap, preferably of galvanized iron, 55 secured upon the top of the base by means of a bolt and nut G, and this cap projects down so as to cover the slot in the opening, the flange of the cap being cut away, as seen at g, upon opposite sides opposite the openings 60 of the base. This cap serves to protect the insulators as well as the base and to exclude the ice and snow and rain.

Modifications in detail may be resorted to without departing from the spirit of the invention or sacrificing any of its advantages. 65

What I claim as new is—

1. An insulator, comprising a base of metal with openings therethrough, one of which has a communicating slot and glass insulators in 70 said openings, substantially as and for the purposes specified.

2. An insulator, comprising a base of metal with openings therethrough, one of which has a communicating slot and glass insulators in 75 said openings, the insulators in one of the openings being formed in semicircular sections, substantially as and for the purposes specified.

3. An insulator, comprising a base with 80 openings therethrough, one of which has a slot communicating therewith, glass insulators in said openings and a cap secured on the top of said base, substantially as and for the purposes specified.

4. An insulator, comprising a base with 85 openings therethrough, one of which has a slot communicating therewith, glass insulators in said openings and a cap secured on the top of said base, said cap having a depending flange cut away upon opposite sides 90 opposite said openings, substantially as and for the purposes specified.

In testimony whereof I have signed this specification in the presence of two subscribing witnesses. 95

ESTEN PELOUBET.
